[57] CLAIM

The ornamental design for a pacifier cover, as shown and described.

DESCRIPTION

FIG. 1 is a top plan view of a pacifier cover showing my new design in open condition;

FIG. 2 is a front elevational view thereof in closed condition;

FIG. 3 is a front elevational view thereof in open condition, the rear elevation view being identical;

FIG. 4 is a bottom plan view thereof; and,

FIG. 5 is a right side elevational view thereof, the left side elevational view being identical thereto.

The broken line showing of the pacifier in FIGS. 2-5 is for illustrative purposes only and forms no part of the claimed design.
